UNITED STATES PATENT OFFICE.

STANLEY W. PALMER, OF BEAVER DAM, WISCONSIN, ASSIGNOR TO SILAS McCLURE,
OF BEAVER DAM, WISCONSIN.

HIGH-CLOSET BRACKET FOR RANGES.

1,400,569.

Specification of Letters Patent. Patented Dec. 20, 1921.

Application filed January 21, 1921. Serial No. 438,825.

To all whom it may concern:

Be it known that I, STANLEY W. PALMER, a citizen of the United States, residing at Beaver Dam, Wisconsin, in the county of Dodge, State of Wisconsin, have invented certain new and useful Improvements in High-Closet Brackets for Ranges; and I do hereby declare the following to be a full, clear, and exact description of the invention, 10 such as will enable others skilled in the art to which it appertains to make and use the same.

My invention is an improvement in stoves and ranges, and relates to high closet and 15 splasher back supporting means, of the character used for connecting the closet to the range in spaced relation above the top thereof, and for holding the splasher back in proper position.

20 The invention has for its object to provide simple inexpensive and ornamental brackets, having means for connecting the same to the range and to the closet, and having independent means for clamping the edges of 25 the splasher back in such manner that the brackets will provide a finish for the ends of the back.

A further object is to provide an improved 30 connection between the panels of the splasher back, that will firmly connect the panels without the necessity for bolts, rivets and the like, and to provide a high closet having a depending skirt or flange for covering the connection between the same and the bracket, 35 for holding the closet from lateral movement with respect to the brackets, and for providing an ornamental finish for the outer edge and front end of the bracket top.

In the drawings—

40 Figure 1 is a perspective view showing the improved range,

Fig. 2 is an end view,

Figs. 3 and 4 are sections on the lines 3—3 and 4—4 respectively of Fig. 2,

45 Fig. 5 is a vertical section through the collar top and lower end of splasher back,

Fig. 6 is a partial vertical section at the junction of the high closet and splasher back.

50 In the present embodiment of the invention, the range 1 which may be of any suitable or desired construction, is provided with the high closet 2, supported by the brackets to be described, and the splasher back is arranged between the closet and the

range top at the rear thereof. This back consists of panels 3, three of which are provided in the present instance, and they extend between the brackets, and between the high closet and the range top. Each of the 60 brackets, of which two are provided, one at each end of the high closet, is a channel plate consisting of a body 4 and side walls 5 and 6. At each end of the body there is an angular extension 7 and 8 respectively, which 65 are in the present instance spot welded to the body of the bracket. The extension 7 is designed to engage the bottom of the high closet, and the extension 8 is designed to be connected with the range top frame, and 70 openings are provided in the said extension 8 for engagement by bolts or rivets to connect the parts. The extension 7 has depending perforate lugs 9 at its outer edge, which are adapted for connection with the high 75 closet 2. Between the extension 7 and 8 and the body of the bracket there is arranged a curved brace 10. This brace in the present instance is a tubular body elliptical in cross-section, and the ends of the brace are connected to the extensions 7 and 8 at the ends 80 remote from the bracket body, by spot welding or the like. Referring to Fig. 2 it will be seen that the extension 7 is offset downwardly at the end remote from the bracket 85 body to engage the brace. The brace is connected to the body of the bracket by a connector and spacer 12 which may be of cast material, and may be connected to the brace and bracket body in any suitable or desired 90 manner. In the present instance the connection is by means of a screw 13. The opposite side edges of the connector and spacer are shaped to fit the brace and bracket body, and that edge adjacent to the brace is concave to receive said brace.

The closet 2 is provided with a depending skirt or flange 15, which when the high closet is in place on the tops of the brackets, that is on the extensions 7, and on the top edges 100 of the splasher back panels, will depend below the extension, and will lap upon the rear faces of the splasher back panels. The front portion of the flange will extend over the upper end of the brace 10, and will form a 105 finish for the said upper end, and for the extension 7 and will cover and conceal the means which are used for connecting the flange to the lugs 9. At the rear of the closet, the flange will cover and conceal the 110

junction of the splasher back panels and the closet, and will provide a neat finish at this joint. The flange 15 is connected to the lugs 9, by means of bolts or rivets 16 which are 5 passed through registering openings in the flange and in the lugs.

Referring to Fig. 3 it will be seen that the flange 6 is of less height than the flange 5, and the outermost edges of the lateral 10 splasher back panels will lap over this flange, bearing against the flange. A clamping strip 17 is provided for clamping the panel to the flange 6. This strip has an outwardly offset portion 18 which is offset far enough 15 from the body of the strip, to engage over the splasher back panel, as clearly shown in Fig. 3, when the body of the strip rests upon the body of the bracket within the channel. The edge of the splasher back 20 panel is clamped between the free edge of the side wall 6 and the outwardly offset portion 18 of the clamping strip. Each side edge of each panel is flanged laterally as indicated at 19, and the flanges 19 at the 25 outer edges of the lateral panels extend between the side wall 6 of the bracket and the connection between the body of the strip 17 and the offset portion 18. Thus these flanges 19 would prevent disengagement of 30 the splasher back panels by movement away from the brackets. The arrangement also provides a slidible connection permitting the parts to adjust themselves to expansion and contraction due to temperature changes. 35 The body of the strip 17 has an opening through which the screw 13 passes, and the screw clamps the strip to the body of the bracket within the channel. The lateral splasher back panels are thus clamped at the 40 back of the bracket, in such manner that the bracket provides a species of column at the end of the splasher back, thus making a finish at the said end. Since however, the flange 5 extends rearwardly of the rear 45 face of the splasher back panel, the connection between the splasher back panel and the bracket is hidden and concealed by the said wall, except when looking from the rear. When the stove or range is placed 50 against the wall in the usual manner, the particular arrangement of the brackets provides an ornamental finish at each end.

In Fig. 4 there is shown the method of 55 connecting the panels 3 of the splasher back to each other. The connection comprises a channel plate consisting of a body 20 and side walls 21, and each side wall has an outwardly extending flange 22 at its free edge. The panels 3 are flanged at their side edges, 60 as before stated, the flanges being indicated at 19, and these flanges abut the outer faces of the side walls 21. The rear faces of the panels abut the flanges or webs 22, and thus the panels are limited in their movement 65 toward each other and in their movement

rearwardly. The channel plate is in fact arranged between the panels, with the flanges 19 abutting the side walls thereof.

In order to hold the panels in abutting relation with the channel plates 20-21, I 70 provide a holding strip 23. This strip is adapted to be superposed on the body 20 of the channel plate, on the opposite face from the side walls, that is on the front of the splasher back. The side edges of the strip 75 have flanges 24 which overlie the body of the strip in spaced relation, and these flanges are so proportioned and so spaced from the body of the strip, that the free edges thereof will engage within the angle 80 between the flanges 19 and bodies of the panels, and will press said angles closely into the angles between the webs 22 and the side walls 21. The strip 23 is spot welded to the body of the channel plate. Thus an 85 interlocking joint is provided which at the front of the splasher back presents a raised appearance giving an impression of strength and rigidity, as well as being ornamental. The panels of the back are thus 90 set off from each other.

Thus there is provided a panel connection consisting of the plate which is adapted to be arranged between the panels, and which has abutments for engaging the 95 panels to limit their movement toward each other, and to limit their movement laterally in one direction, together with a finishing and clamping strip coöperating with the plate and having means in connection therewith for pressing the panels toward the abutments. The lower ends of the splasher back panels as shown more particularly in Fig. 5 have flanges 25 at their lower edges, 100 the said flanges extending rearwardly and upwardly, and these lower ends of the panels are adapted to engage the collar top 26 of the stove or range in the manner shown in Fig. 5. This top has a rearwardly facing shoulder 27, and upstanding lugs 105 28 spaced apart from the shoulder, and the panel is received between the lugs and the shoulder. Thus the lower ends of the panels are anchored against the forward and rearward movement, but yieldingly to permit expansion and contraction. All of the connections between the splasher back, the high closet, the brackets and the stove top 110 are slidble connections, so that there will be no warping of the splasher back because 115 of temperature changes.

The splasher back is held closely against the flange 15 of the high closet at the rear of the closet, by means of angle plates 29. These plates 29 are secured to the bottom 120 of the high closet, by spot welding or the like, and each plate consists of a portion secured to the closet, and a depending portion, which is spaced far enough from the flange to receive the splasher back. The 125 130

angle plates 29 are preferably placed at the panel connections, as shown in Fig. 6, and as shown in said figure, the tops of the splasher back panels 3 have rearwardly 5 bent upper edges 30 stiffening the tops of the panels. Referring to Fig. 6 it will be seen that the bottom of the high closet has a downwardly turned flange which is received within a seam in the flange 15, which 10 is a continuation of the rear wall.

I claim:

1. In stove and range construction, a bracket adapted to be arranged between the high closet and the stove or range, the body 15 of the bracket being channel shaped, and the channel facing rearwardly and having the inner wall thereof of less height than the outer wall, and a holding strip secured to the bracket and overlying the said wall to 20 clamp the splasher back to the said wall.

2. In stove and range construction, a bracket adapted to be arranged between the high closet and the body of the stove or range, said bracket having a channel shaped 25 body, the channel facing rearwardly, the inner wall of the channel being of less height than the outer wall, and a holding strip secured within the channel to the body and having a portion overlying the wall of less 30 height to clamp the splasher back between said wall and the said portion.

3. In stove and range construction, a bracket for connecting the high closet and the splasher back to the body of the stove 35 or range, and comprising a channel shaped body having at each end an angular portion extending in the opposite direction to the walls of the channel and adapted for connection with the high closet and the 40 range respectively, the inner channel wall of the bracket being of less height than the outer wall, and a holding strip detachably connected to the body of the bracket and extending over said channel wall to clamp 45 the splasher back in place.

4. In stove and range construction, a bracket for connecting the high closet and the splasher back to the body of the stove or range, and comprising a channel shaped 50 body having at each end an angular portion extending in the opposite direction to the walls of the channel and adapted for connection with the high closet and the range respectively, the inner channel wall of the bracket being of less height than the outer 55 wall, and a holding strip detachably connected to the body of the bracket and extending over said channel wall to clamp the splasher back in place, said splasher back 60 having its edge forwardly flanged for engaging the side wall to prevent disengagement of the parts.

5. In stove and range construction, brackets adapted to be arranged between the high 65 closet and the splasher back for supporting

the high closet, each bracket being channel shaped and arranged with the channel facing rearwardly, and having means in connection with the inner wall of the channel for engaging the splasher back to clamp the 70 same, the outer wall of the channel extending rearwardly of the said means and the splasher back for the purpose specified.

6. In stove and range construction, the combination with the high closet and the 75 range body, of brackets adapted to be arranged at the ends of the closet between the same and the body for supporting said body, each bracket having at its upper end a forwardly extending portion underlying the 80 closet and a curved brace connected at its upper end to the said portion and intermediate its ends to the body, the closet having a depending flange covering the upper end of the brace and the underlying portion of 85 the bracket.

7. A bracket of the character specified, comprising a body of channel shape having at each end an angular portion extending in the opposite direction to the walls of the 90 channel, and a clamping strip within the channel and having an offset portion at one edge overlying the free edge of one channel wall, said strip being detachably connected to the bracket. 95

8. In stove and range construction, the combination with the stove body, the high closet, and the splasher back, of a common means for connecting the high closet and the splasher back to the body, said means comprising brackets each having angular portions at its ends for connection with the closet and the stove body respectively, and a securing strip detachably connected with the rear face of the body of each bracket for clamping 100 the edge of the splasher back to the bracket. 105

9. In stove and range construction, the combination with the high closet, of a bracket for supporting the same and comprising a body of channel shape having at each end an angular portion extending in the opposite direction to the walls of the 110 channel, and a clamping strip within the channel and having an offset portion at one edge overlying the free edge of one channel wall, said strip being detachably connected to the bracket, the closet having a depending flange fitting about the outer faces of the brackets and of the splasher back at its upper end. 115

10. In stove and range construction, the combination with the collar top, the high closet, and the splasher back, of supporting brackets at the ends of the closet, each bracket comprising a body having means for clamping the adjacent end of the splasher back, and angular portions at the ends of the body for connection with the collar top and the high closet, a curved brace between 125 130

the said portions and the body, the high closet having a depending flange fitting around the upper ends of the brackets and the top of the splasher back hiding the connection and forming a finish for the parts.

11. In stove and range construction, a splasher back panel connection, comprising in combination with the panels, of a channel plate adapted to fit between the adjacent ends of the panels with the said ends abutting the side walls of the channel, said walls having means for limiting the movement of the panels away from the body of the plate, and the panels being flanged toward the body, and a holding strip lying on the body of the plate on the offset face from the channel, the side edges of the strip having overlying flanges engaging the panels at the junctions of the flanges of the panels there-
20 with.

12. In stove and range construction, a splasher back panel connection comprising a plate adapted to be seated between the panels and having abutments for engagement by the panels to limit their movement toward each other and laterally in one direction, and a clamping and finishing strip connected with the plate and having means for pressing the panels against the limiting abutments, said strips and the panels having interengaging means for preventing movement of the panels away from the plate.

13. In stove and range construction, a splasher back panel connection, comprising a plate adapted to be arranged between the panels and having abutments for engage-

ment by the panels to limit their movement toward each other and laterally in one direction, and a finishing and clamping strip 40 coöperating with the plate and having means for pressing the panels toward the abutments.

14. In stove and range construction, a splasher back panel connection, comprising a 45 plate adapted to be arranged between the panels and having abutments for engagement by the panels to limit their movement toward each other and laterally in one direction, and a finishing and clamping strip 50 coöperating with the plate and having means for pressing the panels toward the abutments, said panels being slideable vertically with respect to the said last-named means.

15. A panel connection, comprising in 55 combination with the panels of a plate adapted to be arranged between the adjacent edges of the panels and having abutments for limiting the movement of the panels toward each other and laterally in one 60 direction, and a clamping and finishing strip coöperating with the plate and having means for holding the panels against the abutments.

16. In stove and range construction, the 65 combination with the high closet having a depending flange, and the splasher back fitting within the flange, of means for holding the splasher back against the flange, said means comprising angle plates secured 70 to the high closet bottom and spaced apart from the flange to receive the splasher back.

In testimony whereof I affix my signature.
STANLEY W. PALMER.
